UNITED STATES PATENT OFFICE

WILFRED R. WOOD, OF LONDON, ENGLAND, ASSIGNOR TO INTERNATIONAL COMBUSTION ENGINEERING CORPORATION, OF NEW YORK, N. Y., A CORPORATION OF DELAWARE

STEAM GENERATOR

Original application filed August 20, 1925, Serial No. 51,294. Divided and this application filed September 16, 1927. Serial No. 219,856.

This invention relates to steam generators of the type in which the boiler is furnace shaped, i. e., it is its own furnace whereby the evaporating surfaces are subject to radiant heat and very high capacities are obtainable with relatively small installations.

This application is a division of my co-pending application Serial No. 51,294, filed August 20th, 1925.

One of the primary objects of my invention is to burn the fuel effectively in such a generator.

Another object is to not only effectively liberate heat units in such an installation but also to effectively utilize the same.

How the foregoing, together with such other objects and advantages as may herein-after appear, or are incident to my invention, are realized, is illustrated in preferred form in the accompanying drawings, wherein—

Fig. 1 is a vertical section through a boiler installation embodying my invention, certain of the parts appearing in elevation,

Fig. 2 is a fragmentary section taken on the line 2—2 of Fig. 1, and

Fig. 3 is a diagrammatic plan view illustrating the disposition of the nozzles for introducing fuel into the combustion chamber.

In the drawings I have illustrated a furnace shaped boiler A, the side walls of which are comprised of sets of tubes 3, one of which only appears in the drawings; the front wall by a set of tubes 4; and the rear wall by the bank of tubes 5 of the upright boiler unit 6.

The tubes of the sets of tubes 3, 3 and 4 are preferably provided with longitudinal fins as are also the tubes of the innermost and outermost rows of tubes of the bank of tubes 6. The tubes are arranged so that the fins substantially abut whereby a wall is formed. Certain of the fins are interrupted to provide inlet openings 7 for a purpose hereinafter appearing. The fins of the innermost row of tubes of the bank 5 extend

from the lower drum of the boiler unit 6 to a point short of the upper drum and the fins of the outermost row extend from the upper drum to a point short of the lower drum. Thus a passage is formed for the gaseous products of combustion, the gas on leaving the

combustion chamber passing through the outlet 8 at the top, down over the tubes of the bank of tubes 6 and out through the offtake 9 at the bottom into the stack or flue 10 under influence of draft. It will be noted that the fins of the innermost row are of such extent that such row constitutes the rear wall of the furnace shaped boiler.

A set of tubes 11 extends across the bottom of the boiler thus formed and constitutes a water screen for the boiler, the tubes being relatively widely spaced to permit gravitating refuse particles to pass therebetween. A set of tubes 12 extends across the top of the boiler. It is to be noted that the bottom tubes 11 incline upwardly toward the front wall and that the top tubes incline upwardly toward the boiler unit 6 and the bottom set of tubes is connected at one end into the header 13 which, in turn, is connected with the lower drum of the unit 6 by means of downcomer tubes and at the other end into the bottom header 14 of the set of tubes 4. The top set of tubes 12 is connected at one end into the upper header 15 of the set of tubes 4 and at the other end into the upper drum of the unit 6. The tubes 3 of the side walls are connected at their lower ends into headers 16 and at their upper ends into headers 17, the lower headers being connected with the lower drum of the boiler unit by downcomers 18 and the upper headers being connected with the upper drum of the boiler unit by upcomers 19. Thus it will be seen that the circulation in sets of tubes 11, 4, 12, 85 3, 3 and the front row of tubes of the bank 6 is in an upward direction. Inasmuch as there are a greater number of the tubes 4 than of the tubes 11 an adequate supply of water for the header 14 may be secured by providing downcomers 14a which supplement the tubes 11.

Suitable sheathing is provided to enclose the front, top and side water walls, and an ash hopper 20 is provided below the combustion chamber for the gravitating refuse which may be removed through the valve controlled opening 21.

Pulverized fuel with carrying air is introduced into the combustion chamber at the

lower part thereof by means of nozzles 22 located at each corner of the chamber, which nozzles, as will be clear from Fig. 3, are set so as to deliver the fuel tangentially to a circle having its center in the axial line of the chamber whereby a whirl or vortex is set up, the axis of which is substantially vertical. Air under pressure is admitted around the entering fuel through the openings 23 around 5 the nozzles, which air is supplied from the air heater 24 through the medium of the duct 25. Air, in addition to that admitted with the fuel and around the nozzles may be introduced into the combustion chamber 10 through a plurality of air pipes 26 located in the openings 7 hereinbefore mentioned, which pipes receive their air from the duct 27 which, in this instance, is a subdivision of the preheated air duct 25.

15 20 In order to prevent the flame from possibly burning downward through the water screen 11, damper controlled air openings 28 may be provided in the ash hopper 20. Air so admitted tends to lift the fuel and flame 25 stream.

It will be observed from the foregoing that the furnace shaped boiler proper has an updraft. Pulverized coal particles are not all of the same degree of fineness and in a steam 30 generator of this type which is fired from above, instead of below as herein shown, the heavier particles may pass out of the combustion space proper without being consumed. In installations fired from above the 35 downdraft and gravity cooperate to reduce the length of time such heavier particles remain in the combustion space. By firing from below as herein set forth the updraft counteracts gravity and the heavier particles 40 are drawn relatively slowly upward thru the combustion space and this coupled with the whirling or vortical motion of the fuel and flame stream affords ample opportunity for 45 complete combustion of the heavier particles. Ordinarily no appreciable loss will be 50 encountered by unconsumed fuel entering the ash pit, but if operating conditions are such where this might result, the inlets 28 are employed as above pointed out.

55 The introduction of the coal stream in the manner above described secures mixture of the coal and combustion air in the combustion space and an intensely hot flame results. The temperature head of the furnace is further increased by the preheating of the combustion air. Thus there is a very high rate of heat transfer with correspondingly great capacity. As the fuel and flame stream and 60 gases move upwardly the velocity diminishes so that the exit gases travel at a velocity such as to secure effective heat transfer in the bank of tubes 6, the major portion of which constitutes what may be termed an economizer section integral with the boiler. This economizer section reduces the temperature of the 65

70 relatively hot gases entering the bank to a point where the air preheater is not subjected to an excessive temperature. The air preheater absorbs heat and further reduces the temperature to a point where the final exit temperatures are within allowable limits.

75 Thus the coal is effectively burned and the B. t. u.'s. effectively liberated and effectively applied. Maximum efficiency with maximum capacity from a small installation are thus ensured.

I claim:—

1. In a pulverized fuel burning setting, the combination of a furnace-shaped boiler having its walls defined by upright steam evaporating boiler tubes, downcomer means supplying the lower ends of the tubes, an outlet in the upper part of the boiler for the gaseous products of combustion, and means for introducing pulverized fuel into the lower part of the combustion space including burners substantially at the corners arranged to tangentially deliver the fuel into the combustion space to produce a vortical flame, the axis of which is perpendicular whereby the most intense combustion is opposite the lower end portion of the tubes where the mixture in the tubes is most dense and whereby said portions of the tubes are subject to both radiant 90 heat and heat of convection.

2. In a pulverized fuel burner setting, the combination of a furnace-shaped boiler having its walls defined by upright steam evaporating boiler tubes, downcomer means supplying the lower ends of the tubes, an outlet in the upper part of the boiler for the gaseous products of combustion, and means for introducing pulverized fuel into the lower part of the combustion space including burners substantially at the corners arranged to tangentially deliver the fuel into the combustion space to produce a vortical flame the axis of which is perpendicular whereby the most intense combustion is opposite the lower end portion of the tubes where the mixture in the tubes is most dense and whereby said portions of the tubes are subject to both radiant heat and heat of convection, the tubes defining certain of the walls being finned.

3. In a pulverized fuel burning setting, the combination of a furnace-shaped boiler having its walls defined by upright steam evaporating boiler tubes, a bank of upright convection tubes grouped with the upright tubes of one of the walls, downcomer means supplying the lower ends of the tubes, an outlet in the upper part of the boiler for the gaseous products of combustion, and means for introducing pulverized fuel into the lower part of the combustion space including burners substantially at the corners arranged to tangentially deliver the fuel into the combustion space to produce a vortical flame the axis of which is perpendicular, whereby the most in- 130

ense combustion is opposite the lower end portion of the tubes where the mixture in the tubes is most dense and whereby said portions of the tubes are subject to both radiant heat and heat of convection.

In testimony whereof I have hereunto signed my name.

WILFRED R. WOOD.
